UNITED STATES PATENT OFFICE.

WILLIAM R. DELL, OF PHILADELPHIA, PENNSYLVANIA, ASSIGNOR OF ONE-HALF TO
ALBERT DELL, OF PHILADELPHIA, PENNSYLVANIA.

DESIGN FOR A CAN-OPENER.

55,984.

Specification for Design.

Patented Aug. 10, 1920.

Application filed December 23, 1919. Serial No. 347,021. Term of patent 7 years.

To all whom it may concern:

Be it known that I, WILLIAM R. DELL, a citizen of the United States, residing at Philadelphia, in the county of Philadelphia and State of Pennsylvania, have invented a new, original, and ornamental Design for a Can-Opener, of which the following is a specification, reference being had to the accompanying drawing, forming a part thereof.

Figure 1—is a plan view.

Fig. 2—is a view looking at one side, and
Fig. 3—is a view looking at the opposite side.

I claim:

The ornamental design for a can opener as shown.

WILLIAM R. DELL.
